[57] CLAIM

The ornamental design for a cabinet for optical imaging of fingerprints, as shown and described.

DESCRIPTION

FIG. 1 is a top, front and right side perspective view of a cabinet for optical imaging of fingerprints, showing our new design;

FIG. 2 is a front elevational view thereof;

FIG. 3 is a back elevational view thereof;

FIG. 4 is a right side elevational view thereof;

FIG. 5 is a left side elevational view thereof;

FIG. 6 is a top plan view thereof;

FIG. 7 is a top, front and right side perspective view of a second embodiment of a cabinet for optical imaging of fingerprints;

FIG. 8 is a front elevational view thereof;

FIG. 9 is a back elevational view thereof;

FIG. 10 is a right side elevational view thereof;

FIG. 11 is a left side elevational view thereof; and,

FIG. 12 is a top plan view thereof.
